US0D1045955S

(12) **United States Design Patent** (10) **Patent No.:** **US D1,045,955 S**
(45) **Date of Patent:** **** Oct. 8, 2024**

(54) **CAMERA**

(71) Applicant: **HANGZHOU HIKVISION DIGITAL TECHNOLOGY CO., LTD.**, Hangzhou (CN)

(72) Inventors: **Fengmin Zhang**, Hangzhou (CN); **Peng Xu**, Hangzhou (CN); **Liang Ying**, Hangzhou (CN); **Zhan Ye**, Hangzhou (CN)

(73) Assignee: **HANGZHOU HIKVISION DIGITAL TECHNOLOGY CO., LTD.**, Hangzhou (CN)

(**) Term: **15 Years**

(21) Appl. No.: **29/740,349**

(22) Filed: **Jul. 2, 2020**

Related U.S. Application Data

(63) Continuation of application No. 29/656,030, filed on Jul. 10, 2018, now Pat. No. Des. 892,895.

CLAIM

The ornamental design for a camera, as shown and described.

DESCRIPTION

FIG. 1 is a front view of a camera showing our new design. FIG. 2 is a rear view of our new design shown in FIG. 1. FIG. 3 is a left-side view of our new design shown in FIG. 1.

FIG. 4 is a right-side view of our new design shown in FIG. 1.

FIG. 5 is a top view of our new design shown in FIG. 1. FIG. 6 is a bottom view of our new design shown in FIG. 1; and,

FIG. 7 is a perspective view of our new design shown in FIG. 1.

The broken line in the drawings illustrate portions of the camera and form no part of the claimed design. The dot-dash broken lines in the drawings define the bounds of the claim and form no part thereof.

1 Claim, 7 Drawing Sheets
